UNITED STATES PATENT OFFICE

2,605,110

TOOL WITH SEPARABLE HANDLE

Sidney Blum, Forest Hills, N. Y.

Application March 9, 1951, Serial No. 214,815

4 Claims. (Cl. 279—96)

1

The present invention relates to screw-drivers and especially to a tool of this type wherein the blade or shank is separable from the handle to enable the insertion of blades of various sizes and shapes into the single handle.

In tools of this type as heretofore used the handle is usually provided with a hollow sleeve extending longitudinally of its axis into which the shank telescopically fits. In order to hold the sleeve within the handle and to prevent rotation thereof during use, the sleeve has been driven into an opening in the handle to provide simply a tight frictional engagement, or the sleeve has been provided with external lugs engaging the interior wall of the opening in the handle. Such construction has proven unsatisfactory in use because the frictional engagement of a cylindrical shaped sleeve is too unreliable in actual usage of the tool and frequently results in the tool becoming useless after a short period of time due to the sleeve rotating within the handle under strain. In instances where the sleeve is provided with external lugs which are embedded in the handle this tends to weaken the handle wall frequently causing it to split and break thus again destroying the usefulness of the tool.

It is accordingly the object of the present invention to provide a screw-driver which is economical to manufacture and wherein the shank is separable from the handle to enable the insertion of blades of various sizes and shapes and a longitudinally disposed sleeve firmly anchored in the handle telescopically receives the shank.

Another object of the present invention is the provision of a screw-driver in which blades of various sizes and shapes may be readily inserted and removed from the handle and wherein the latter is provided with a sleeve for telescopically receiving the shanks of such blades with the sleeve positively secured to the handle against rotation under exceedingly severe strain.

Still further objects of the present invention will become obvious to those skilled in the art by reference to the accompanying drawing wherein,

Fig. 1 is an elevational view of a screw-driver constructed in accordance with the present invention showing the shank of a customary blade inserted in the handle;

Fig. 2 is a fragmentary view of a "Phillips" type blade which may be substituted for the usual type blade of Fig. 1;

Fig. 3 is a fragmentary exploded cross-sectional view on a somewhat larger scale of the screw-driver as shown in Fig. 1 or 2;

2

Fig. 4 is a fragmentary cross-sectional view similar to Fig. 3 but showing the shank inserted into the sleeve within the handle;

Fig. 5 is a view taken on the line V—V of Fig. 3 and looking in the direction indicated by the arrows;

Fig. 6 is a cross-sectional view taken on the line VI—VI of Fig. 5;

Fig. 7 is a cross-sectional view taken on the line VII—VII of Fig. 3;

Fig. 8 is a cross-sectional view taken on the line VIII—VIII of Fig. 3, and

Fig. 9 is an exploded perspective view of the sleeve with its internal split bushing employed to hold the shank within the handle in accordance with the present invention.

Referring now to the drawings in detail the screw-driver of the present invention as therein shown comprises a handle 5 which may be of wood but preferably is formed of cellulose or the like. A sleeve 6 extends longitudinally of the axis of the handle for the telescopic reception of the shank 7 of a customary blade 8, or of a "Phillips" type blade 9. As shown in the several figures, the sleeve 6 is provided with a head 10 of slightly larger diameter than the rest of the sleeve, which thus forms a shoulder 12 resting against the end of the handle 5 for limiting the depth that the sleeve is disposed within the handle 5.

By reference more particularly to Fig. 9, it will be noted that the transverse surface of the sleeve 6 is provided with small notches 13 disposed at 90° with respect to each other, with a pair of such notches spaced 180° apart receiving a lug 14 carried by an end of a split bushing 15. This latter bushing is formed of two identical matching halves 16 and 17 each one of which has a cut-out portion, so that when the two halves are joined together, as more clearly seen from Fig. 9, a pair of longitudinal slots 18 and 19 are provided in the bushing which are 180° apart and align with the remaining pair of notches 13 when the lugs 14 engage the other pair of notches 13.

The diameter of the split bushing 15 corresponds approximately to the internal diameter of the sleeve 6 and when the latter is slipped over the two halves 16 and 17 of the bushing they are held together forming the slots 18 and 19, by engagement of the lugs 14 with one pair of the notches 13. The lower end of each bushing half 16 and 17 is provided with a pair of prongs 20 and 22 which, although extending generally in a longitudinal direction, are bent slightly outward, as can be seen more clearly in Figs. 6 and 9.

The assembly comprising the split bushing

15 surrounded by the sleeve 6 is pressed or driven into a longitudinal opening 23 provided in the handle 5 until the shoulder 12 rests against the end of the handle at which time the projecting prongs 20 and 22 will be embedded firmly into the material of the handle which prevents rotation of the bushing 15 under any twisting strain. Since the lugs 14 engage one of the pairs of notches 13 the sleeve 6 is likewise prevented from rotation under strain by the rigidity with which the bushing 15 is held within the handle 5. However, the frictional engagement between the sleeve 6 and the interior of the handle may be enhanced by the provision of a knurled surface 24 on the outside of the sleeve 6.

Referring now more particularly to Fig. 3, it will be noted that the screw-driver shank, whether of the usual bladed end or of the "Phillips" type, is provided with a pair of longitudinally extending swaged key surfaces 25 disposed 180° relative to each other and of a thickness sufficient to slide through the remaining pair of notches 13 in the sleeve 6 and downwardly of the aligning slots 18 and 19 provided in the split bushing 15. The latter being anchored at its lower end by the prongs 20 and 22 and split along its entire length with the upper end held by the lugs 14 within the surrounding sleeve 6, provides sufficient frictional engagement to retain the shank 7 within the handle until it is desired to remove the shank by pulling it out of the handle 5. While disposed within the handle 5 during usage, however, the screw-driver can be subjected to all the necessary twisting strain encountered, without fear of the shank 7 rotating in the retaining assembly comprising the sleeve 6 and split bushing 15, or the latter rotating under such twisting strain, because the assembly is held against rotation by the embedded prongs 20 and 22 and the lugs 14 together with the frictional engagement of the sleeve 6 and its knurled surface 24 and the interior of the handle 5. The shank 7 of the blade may also be provided with a knurled portion on a part of its exterior surface, if desired, to form a gripping surface for pliers or a wrench.

It thus becomes obvious to those skilled in the art that a screw-driver is provided by the present invention wherein the shank is separable from the handle to enable the insertion of blades of various sizes and shapes therein. Moreover, when inserted in the handle the shank is not only retained securely therein against accidental displacement but due to the retaining assembly of an anchored split bushing and a surrounding sleeve, the shank is prevented from turning within the handle throughout a long useful life of the tool. Although one specific embodiment of the present invention has been shown and described it is to be understood that still further modifications thereof may be made without departing from the spirit and scope of the appended claims.

I claim:

1. A tool comprising a handle having a recess extending longitudinally from one end, a cylindrical sleeve disposed in said recess in tight frictional engagement with said handle and provided with notches, a bushing positioned interiorly of said sleeve provided with lugs engaging the notches in said sleeve and having prongs embedded in said handle to prevent turning of said bushing and sleeve under stress and said bushing having slots aligning with other notches in said sleeve, and a tool shank having

5 projections engageable with the slots in said bushing to retain said shank in said handle and to rotate said shank by said handle without relative rotation therebetween.

2. A tool comprising a handle having a recess extending longitudinally from one end, a cylindrical sleeve disposed in said recess in tight frictional engagement with said handle and provided with notches in the outer end thereof, a bushing positioned interiorly of said sleeve provided with lugs at one end engaging some of the notches in the outer end of said sleeve and having prongs at its inner end embedded in said handle to prevent turning of said bushing and sleeve under stress, and said bushing having slots aligning with other notches in the outer end of said sleeve, and a tool shank having projections engageable with the slots in said bushing to retain said shank in said handle and to rotate the latter by said handle without relative rotation therebetween.

3. A tool comprising a handle having a recess extending longitudinally from one end, a cylindrical sleeve disposed in said recess in tight frictional engagement with said handle and provided with notches in the outer end thereof, a split bushing formed of two halves held together by said sleeve with each half provided with a lug at one end engaging one of the notches in the outer end of said sleeve and each half having a pair of prongs at its other end embedded in said handle to prevent turning of said bushing and sleeve under stress, and said bushing having slots at the junction of said halves aligning with other notches in the outer end of said sleeve, and a tool shank having projections engageable with the slots in said bushing to retain said shank in said handle and to rotate the latter by said handle without relative rotation therebetween.

4. A tool comprising a handle having a recess extending longitudinally from one end, a cylindrical sleeve disposed in said recess in tight frictional engagement with said handle and provided with notches in the outer end thereof disposed at 90° relative to each other, a split bushing formed of two halves held together by said sleeve with each half provided with a lug at one end engaging one of the notches in the outer end of said sleeve which are disposed 180° apart and each half having a pair of prongs at its other end embedded in said handle to prevent turning of said bushing and sleeve within said handle under stress, and said bushing having slots at the junction of said halves aligning with the remaining notches in the outer end of said sleeve which are 180° apart, and a tool shank having projections engageable with the slots in said bushing to retain said shank in said handle and to rotate the latter by said handle without relative rotation therebetween.
